(57) **CLAIM**

The ornamental design for a wheel rim, as shown and described.

DESCRIPTION

FIG. 1 shows a front view of my design for a wheel rim; FIG. 2 shows an enlarged front view of a portion of the design according to the invention;

FIG. 3 shows a perspective view of a portion of the outer rim of the design according to the invention;

FIG. 4 shows a perspective view of the front of the design according to the invention;

FIG. 5 shows a side perspective view of the design according to the invention;

FIG. 6 shows an enlarged view of a portion of the front of the design according to the invention;

FIG. 7 shows a perspective view of the side and front of the design according to the invention;

FIG. 8 shows another front view of the design according to the invention;

FIG. 9 shows a perspective view of the rear and sides of the design according to the invention;

FIG. 10 shows a perspective view of the rear of the design according to the invention;

FIG. 11 shows a side view of the design according to the invention; and,

FIG. 12 shows another side view of the design according to the invention.
